DUPLICATING MECHANISM

Alfred Marchev, La Grange, Ill., assignor to
Ditto, Incorporated, Chicago, Ill., a corpora-
tion of West Virginia

Application April 5, 1937, Serial No. 135,127

8 Claims. (Cl. 101—132)

This invention relates to duplicating machines and is particularly adapted to be embodied in rotary duplicating machines of the type in which a drum is provided with a gelatin band adapted to receive impressions from master sheets. The impressions are subsequently imparted to copy sheets which are brought into contact with the gelatin surface of the band.

One form of the invention is embodied in a machine of this character, such, for example, as that shown in the prior application of Alfred Marchev, Serial No. 55,969, filed December 24, 1935, for improvements in Duplicating apparatus.

The present invention comprises mechanism of an improved character for preventing damage to the gelatin surface by the initial contact with the platen roller. The improved machine comprises means operable automatically as the forward edge of the gelatin band approaches the platen roller to move the platen roller out of the way and then bring it down upon the gelatin band, thereby avoiding damage to the band by the impact of the roller therewith.

The features and advantages of the invention will appear more readily from the following description, reference being had to the accompanying drawings, wherein a preferred form of the invention is shown.

In the drawings—

Fig. 1 is a plan view of a portion of a duplicating machine embodying the invention, certain parts of the mechanism being broken away for the sake of clearness;

Fig. 2 is a sectional view on the line 2—2 of Fig. 1;

Fig. 3 is a sectional view on the line 3—3 of Fig. 1;

Fig. 4 is a sectional view similar to Fig. 3 and showing a changed position of the parts;

Fig. 5 is a sectional view on the line 5—5 of Fig. 2.

Referring now to the drawings, in which a preferred embodiment of the invention is illustrated, the numerals 10 and 11 indicate side frames of the machine, in which a drum 12 is journaled for rotation. The drum 12 has a gelatin band 13 thereon and is provided with a pair of spindles 14 and 15, upon which the opposite ends of the gelatin band 13 are wound. The drum 12 is mounted upon a shaft 16 and is adapted to be driven from a suitable source of power such as a motor (but not shown) through a reduction gear 17, as will be readily understood. A copy sheet feed table 18 is adapted to support sheets being fed to the drum 12 by means

of a feed unit 19, the details of which will be described more fully hereinafter. Suitable stripping rollers 20 and 21 cooperate with a stripping bar 22 to remove sheets from the drum and deliver the removed sheets to a receiving tray 23, in the usual manner.

The feed unit 19 preferably comprises a framework suitably supported in the side frames 10 and 11. This framework supports a margin bar 24 and a feed chute comprising a guide plate 25, 10 a second guide plate 26, and a lockout device 27. The function and operation of the guide plates 25 and 26, and the lockout device 27, are shown and described in detail in my prior application, Serial No. 44,523, filed October 11, 1935. 15

The feed unit 19 also comprises a sponge rubber platen roller 28, which is yieldingly mounted in a pair of end plates 29 and 30 of the feed unit 19. The platen roller 28 is mounted by means of stub shafts 31 and 32 (see Fig. 1), fixed 20 in the ends of the platen roller 28. Each stub shaft is yieldingly supported in its end frame by a bearing block 33, which rides in a slot 34 provided in the corresponding end frame member 29 or 30. A spring 35 is seated in a recess 35, 25 which opens onto the slot 34. The spring 35 yieldingly presses the bearing blocks 33 downwardly against a set screw 36, which is threaded into a plate 37. The plate 37 is mounted on the end frame member 29 or 30. 30

On the free ends of the stub shafts 31 and 32, a pair of links 39 and 40 are provided. These links, which are outside of the adjacent end frame members 29 and 30, are slotted to receive the shafts 31 and 32, so as to permit a limited 35 amount of play. The links 39 and 40 are connected to a pair of arms 41 and 42, which arms are keyed on a pair of pins 44 and 45, rotatably journaled in the end frames 29 and 30. Inside the frames 29 and 30, the pins 44 and 45 40 have a pair of arms 46 and 47 secured thereto.

In the prior applications hereinbefore mentioned, there is provided a paper guide 48 which, in normal operating position, projects upwardly over the drum in the position shown in Figs. 2, 45 3 and 4. The copy sheets, such as indicated at 49, after being fed from the table 18, lie up against this paper guide until they are let down into contact with the gelatin band 13 on the drum 12. The guide 48 is pivoted to the end 50 plates 29 and 30 by suitable arms 50 and a shaft 51. Each arm 50 carries a roller 52 which is adapted to rest upon the adjacent end plate 29 or 30 when the paper guide is in normal operating position. When the paper guide is moved 55

forward about the shaft 51, the arms 50 at the side of the paper guide engage the free ends of the arms 46 and 47, so as to move the arms 46 and 47 in a counterclockwise direction.

5 The movement of the arms 46 and 47 in a counterclockwise direction lifts the platen roller 28 out of its printing position. This enables the operator to prevent the platen roller 28 from coming in contact with the band 13 any time he 10 desires to do so.

Means are also provided whereby the yielding mounting of the platen roller, by means of the blocks 33 and springs 35, may be utilized to automatically prevent damage to the gelatin band 13.

15 On the side frames 29 and 30, there are mounted a pair of levers 53 and 54. They are supported on pins 55 and 56, mounted on the side frames 29 and 30. Each lever 53 and 54 has an elongated slot 57 therein, which slot receives the corresponding stub shaft 31 or 32, so that, if the levers 53 and 54 are turned about the pins 55 and 56, they will move the stub shafts 31 and 32, and the platen roller 28, toward and away from the position of the platen roller shown in Fig. 3. In order to 20

25 move the levers 53 and 54, the free ends of the levers are turned and flattened to form cam portions 58 and 59. The cam portions curve outwardly at the free ends of the levers, with a smooth curve, as is shown best in Figs. 2 and 3 30 at 60. The drum 12 carries cam rollers 61 and 62 at its opposite ends, which cam rollers are adapted to engage the free ends 58 and 59 of the levers 53 and 54. The position of the rollers 61 and 62 with respect to the advancing edge of the gelatin 35 band 13 is such that the platen roller 28 is lifted by the levers 53 and 54 just as the advanced edge of the gelatin is almost up to the platen roller. The rollers 61 and 62 then pass onto the curved portions 60 of the levers 53 and 54, so as to let the 40

40 platen roller descend gradually and radially onto the gelatin band, or, to be more exact, onto the copy sheet which has been fed between the gelatin band and the platen roller and adhered to the advancing edge of the gelatin band.

45 In this fashion, the impact of the gelatin band against the platen roller is no longer in the direction of rotation of the drum to any appreciable extent. It is possible, with the above mechanism, to quickly bring the platen roller down on the 50 copy sheet at the advancing end of the gelatin band. This is accomplished with the present invention in such a fashion as to prevent damage to the gelatin band by the force of the impact due to the speed of rotation of the drum.

55 In my prior application, Serial No. 55,969, means were provided on the drum and the platen roller to take the impact before the roller contacted the gelatin band. The present invention differs from that by providing means for eliminating the impact.

60 While the preferred embodiment of the invention has been shown and described, it is to be understood that it is capable of many modifications. Changes, therefore, in the construction 65 and arrangement may be made without departing from the spirit and scope of the invention, as disclosed in the appended claims, in which it is the intention to claim all novelty inherent in the invention as broadly as possible, in view of the prior art.

70 Having thus described the invention, what I claim as new and desire to secure by Letters Patent is:

75 1. In a duplicating machine, a duplicating drum, means to rotate said drum, a duplicating

band on said drum, means guiding sheets to said drum, a platen roller adapted to press the sheets against the band on said drum, mounting means for said platen roller including yielding means adapted to hold it in the path of the advancing band, lever means connected with said roller and operable to lift the roller out of the path of said band, and lever engaging means on said drum adapted to move the lever means just in advance of the platen roller meeting the band and thereby cause the platen roller to be lifted over the advancing edge of the band. 5

2. In a duplicating machine, a duplicating drum, means to rotate said drum, a duplicating band on said drum, means guiding sheets to said drum, a platen roller adapted to press the sheets against the band on said drum, mounting means for said platen roller including yielding means adapted to hold it in the path of the advancing band, lever means connected with said roller and 15 operable to lift the roller out of the path of said band, said lever means comprising a lever at each end of said platen roller, and rollers on the drum for engaging said levers. 20

3. In a duplicating machine, a duplicating drum, means to rotate said drum, a duplicating band on said drum, means guiding sheets to said drum, a platen roller adapted to press the sheets against the band on said drum, mounting means for said platen roller including yielding means 30 adapted to hold it in the path of the advancing band, lever means connected with said roller and operable to lift the roller out of the path of said band, said lever means including a manually operable lever and a drum operated lever. 35

4. In a duplicating machine, a duplicating drum means to rotate said drum, a duplicating band on said drum, means guiding sheets to said drum, a platen roller adapted to press the sheets against the band on said drum, mounting means 40 for said platen roller including yielding means adapted to hold it in the path of the advancing band, lever means connected with said roller and operable to lift the roller out of the path of said band, said lever means including a manually operable lever and a drum operated lever, a shaft carrying said platen roller, a link having one end connected to the shaft and the other end connected to said manually operable lever, and said drum operated lever being connected to said 45 shaft. 50

5. In a duplicating machine, a duplicating drum, means to rotate said drum, a duplicating band on said drum, means guiding sheets to said drum, a platen roller adapted to press the sheets 55 against the band on said drum, mounting means for said platen roller including yielding means adapted to hold it in the path of the advancing band, lever means connected with said roller and operable to lift the roller out of the path of said band, stub shafts at the ends of said platen roller and journaled in said mounting means, said lever means being connected to said stub shafts hereby to lift the stub shafts in their mounting means when the lever means is lifted, and lever 60 engaging means on said drum adapted to move the lever means just in advance of the platen roller meeting the band and thereby cause the platen roller to be lifted over the advancing edge of the band. 65

70 6. In a duplicating machine, a duplicating drum, means to rotate said drum, a duplicating band on said drum, means guiding sheets to said drum, a platen roller adapted to press the sheets 75 against the band on said drum, mounting means

for said platen roller including yielding means adapted to hold it in the path of the advancing band, lever means connected with said roller and operable to lift the roller out of the path of said 5 band, stub shafts at the ends of said platen roller and journalled in said mounting means, said lever means being connected to said stub shafts whereby to lift the stub shafts in their mounting means when the lever means is lifted, and lever engaging 10 means on said drum adapted to move the lever means just in advance of the platen roller meeting the band and thereby cause the platen roller to be lifted over the advancing edge of the band, said lever means comprising a lever at each end 15 of said platen roller, and rollers on the drum for engaging said levers.

7. In a duplicating machine, a duplicating drum, means to rotate said drum, a duplicating band on said drum, means guiding sheets to said 20 drum, a platen roller adapted to press the sheets against the band on said drum, mounting means for said platen roller including yielding means adapted to hold it in the path of the advancing band, lever means connected with said roller and operable to lift the roller out of the path of said 25 band, stub shafts at the ends of said platen roller and journalled in said mounting means, said lever means being connected to said stub shafts where-

by to lift the stub shafts in their mounting means when the lever means is lifted, and lever engaging means on said drum adapted to move the lever means just in advance of the platen roller meeting the band and thereby cause the platen 5 roller to be lifted over the advancing edge of the band, said lever means comprising a lever at each end of said platen roller, and rollers on the drum for engaging said levers, said levers having 10 roller engaging surfaces curving away from the drum at the free ends of the levers.

8. In a duplicating machine, a duplicating drum, means to rotate said drum, a duplicating band on said drum, means guiding sheets to said 15 drum, a platen roller adapted to press the sheets against the band on said drum, mounting means for said platen roller including yielding means adapted to hold it in the path of the advancing band, lever means connected with said roller and operable to lift the roller out of the path of said 20 band, and lever engaging means on said drum adapted to move the lever means just in advance of the platen roller meeting the band and thereby cause the platen roller to be lifted over the advancing edge of the band, said lever engaging 25 means comprising a roller carried by the drum.

ALFRED MARCHEV.
